CLAIM

The ornamental design for the chair, as shown and described.

DESCRIPTION

This application is related to commonly assigned, concurrently filed application Ser. No. 29/283,141.

FIG. 1 is an isometric view of the chair of the present design; FIG. 2 is a front elevation view thereof;

FIG. 3 is a right side elevation view thereof, the left side elevation view being a mirror image thereof;

FIG. 4 is a back elevation view thereof;

FIG. 5 is a top plan view thereof; and,

FIG. 6 is a bottom plan view thereof.

In the drawings, the broken lines depict environmental subject matter only and form no part of the claimed design.
